(57) **CLAIM**

The ornamental design for a connector assembly, as shown and described.

DESCRIPTION

FIG. 1 is a top plan view of a joined connector assembly showing our new design in accordance with an embodiment of the invention;

FIG. 2 is a side elevational view thereof;

FIG. 3 is a perspective view of the top and one side of a male sensor connector half of the connector assembly, shown separately for clarity of illustration;

FIG. 4 is a perspective view of the bottom and opposite side thereof;

FIG. 5 is a top plan view thereof;

FIG. 6 is a bottom plan view thereof;

FIG. 7 is a front elevational view thereof;

FIG. 8 is a back elevational view thereof;

FIG. 9 is a side elevational view thereof;

FIG. 10 is a perspective view of the top and one side of the female patient cable connector half of the connector assembly, shown separately for clarity of illustration;

FIG. 11 is a perspective view of the bottom and opposite side thereof;

FIG. 12 is a top plan view thereof;

FIG. 13 is a bottom plan view thereof;

FIG. 14 a front elevational view thereof;

FIG. 15 is a back elevational view thereof; and,

FIG. 16 is a side elevational view thereof.

The broken line showing on the drawing disclosure is for illustrative purposes only and forms no part of the claimed design.
